DESIGN FOR A STORE FRONT

G. William Doerr, Chicago, Ill., assignor to William C. Grunow, Lake Geneva, Wis.

Application July 3, 1940, Serial No. 93,405

Term of patent 14 years

To all whom it may concern:

Be it known that I, G. William Doerr, a citizen of the United States and a resident of the city of Chicago, in the county of Cook and State of Illinois, have invented a new, original, and ornamental Design for a Store Front, of which the following is a specification, reference being had to the accompanying drawings, forming a part thereof.

On the drawings:

I claim:

The ornamental design for a store front, as shown.

G. WILLIAM DOERR.
